RUBBER DOLL

Alice M. Rowe, Akron, Ohio

Application December 27, 1954, Serial No. 33,701

Term of patent 14 years

(Cl. D34—4)

FIG. 1

Figure 1 is a front view of a rubber doll embodying my new design.

Figure 2 is a rear view of the doll of Figure 1.

Figure 3 is a side view of the doll of Figure 1.

I claim:

The ornamental design for a rubber doll, substantially as shown.
